UNITED STATES PATENT OFFICE.

GEORGE N. HINDS, OF MARION, OHIO.

COIN-SEPARATING DEVICE.

1,275,155.

Specification of Letters Patent.

Patented Aug. 6, 1918.

Application filed September 2, 1915. Serial No. 48,635.

To all whom it may concern:

Be it known that I, GEORGE N. HINDS, a citizen of the United States, residing at Marion, in the county of Marion and State 5 of Ohio, have invented new and useful Improvements in Coin-Separating Devices, of which the following is a specification.

This invention is an improved device for separating and classifying coins, and the 10 like, although not limited in its application to this particular class of articles.

One of the objects of the invention is to provide a simple device which will so operate upon, or handle miscellaneous coins, and 15 the like, as to quickly and effectively separate and classify the various denominations, and to deliver each denomination separately from the others. A further object is to provide a device of the character referred to in 20 which the separation and sorting may be carried on continuously.

The invention will be hereinafter fully set forth and particularly pointed out in the claims.

25 In the accompanying drawing:—

Figure 1 is a side elevation of a coin separating device, constructed in accordance with the invention. Fig. 2 is a similar view with the casing removed. Fig. 3 is a longitudinal 30 sectional view.

Referring to the drawing, 10 designates a standard or core, of suitable proportions, preferably constructed of sheet metal to form a cylindrical casing, the ends being closed by 35 caps 11. Extending longitudinally through the core 10, is a supporting rod 12, one end of said rod being projected through the lower end cap 11, and provided with a supporting head 13, engaging a base 14, in such manner 40 that the core is supported in a vertical position, and free to rotate with respect to said base. The rod 12 is secured to the core 10 in any desired manner, such for instance, as passing cross rods 15 transversely there- 45 through, and securing the ends of said cross rods in suitable openings formed in the wall of said core.

Encircling the core or standard 10, are a series of helically arranged plates 16, placed 50 one above the other, the inner edges of the plates being rigidly attached to the core or standard in any suitable or desired manner. Said plates are preferably made of sheet metal sufficiently heavy to support the weight 55 of the coins, or the like, without bending,

while the device is in operation. The plates 16, and their supporting core 10, are surrounded by a cylindrical casing 17, attached to the outer edges of said plates, in suitable manner, and coöperating with the plates to 60 form a plurality of helically arranged chutes. The upper end of the casing 17 is turned inwardly and shaped to form a hopper as shown. Each of the plates is provided with a series of holes 18, with the exception 65 of the lowermost plate, which is imperforate, the holes in the topmost plate being larger than the corresponding openings in any of the plates below it. Likewise, the second plate, while having smaller openings than 70 those of the top plate, is provided with openings that are larger than any of those below it, the arrangement being such that the smallest coins will work through to the bottom plate, and the largest coins will be retained 75 by the top plate, the coins of intermediate sizes being allowed to pass through the holes 18 until they reach a plate having openings too small for them to pass. Each of the helical chutes terminates in a delivery 80 spout 19, and the delivery ends of said spouts are so spaced from each other that the coins delivered by each will not mix with the coins delivered by the others. Attached to the casing 17, is an operating handle 20, provided 85 with a hinge connection which will permit the same to drop down, parallel with the casing, when not in use.

In practice, when it is desired to operate the machine for the purpose of assorting 90 coins, the miscellaneous coins are promiscuously dropped into the device, through the upper open end of the casing 17, which acts as a hopper, and come to rest upon the topmost plate 16. The operator then grasps 95 the handle 20, and oscillates the core or standard, together with the attached plates and casing, upon the base 14. The motion of the device agitates the coins, causing them to move outwardly away from the core 100 or standard and also downwardly through the various helical chutes, the smaller coins dropping through the openings 18 in the respective plates, until they can pass no farther, the respective denominations being 105 readily classified in this manner and separately discharged by the various spouts 19.

Having thus explained the nature of my invention, and described an operative manner of constructing and using the same, al- 110

though without attempting to set forth all of the forms in which it may be made, or all of the forms of its use, what I claim is:—

1. An improved coin separating device comprising a tubular core, a supporting rod attached to said core and extending longitudinally therethrough, means for rotatably supporting the same, a plurality of helical plates attached to and encircling said core or standard to form channels, said plates having openings therein, the openings in each plate being of a size different from those in the other plates, and means whereby said rod may be radially oscillated.
2. An improved coin separating device comprising a tubular core, a supporting rod attached to said core and extending longitudinally therethrough, means for rotatably supporting the same, a plurality of helical plates attached to and encircling said core or standard, a casing surrounding said plates and attached to the outer edges thereof, said casing and said plates coöperating to form helical channels, said plates having openings therein, the openings in each plate being of a uniform size different from those in the other plates, and means whereby said core or standard may be oscillated, said channels having independent downwardly directed delivery chutes inclosed within said casing.
3. An improved coin separating device comprising a vertically disposed core or standard, means for rotatably supporting the same, a plurality of helical plates attached to and encircling said core or standard, a casing surrounding said plates and attached to the outer edges thereof, said casing and said plates coöperating to form helical channels, said casing extending above said channels and having an open top provided with an inturned portion to form a hopper, said helical plates having openings therein, the openings in each plate being of a size different from those in the other plates, and a handle attached to said casing.
4. An improved coin separating device

comprising a tubular core, a supporting rod attached to said core and extending longitudinally therethrough, a base in which said rod is rotatably mounted, a plurality of helical separating channels encircling said core or standard and having bottom openings, the openings in each plate being of a size different from those in the other plates, and means whereby said core or standard and said channels may be oscillated.

5. An improved coin separating device comprising a tubular core, a supporting rod extended longitudinally through said core or standard and having one end projecting below the same, cross rods uniting said supporting rod and said core or standard, a base in which said supporting rod is rotatably mounted, a plurality of helical separating channels encircling said core or standard, and means whereby said core or standard and said channels may be oscillated.

6. An improved coin separating device comprising a tubular core, a supporting rod attached to said core and extending longitudinally therethrough, means for rotatably supporting the same, a plurality of helical plates attached to and encircling said core, a casing surrounding said plates and attached to the outer edges thereof, said casing and said plates coöperating to form helical channels, said plates having openings therein, the openings in each plate being of a size different from those in the other plates, said channels having independent downwardly directed delivery chutes inclosed within said casing, and means whereby said core or standard may be oscillated.

In testimony whereof I have hereunto set my hand in presence of two subscribing witnesses.

GEORGE N. HINDS.
